Attorney

Patented Dec. 20, 1927.

UNITED STATES PATENT OFFICE.

ALFRED H. SORELL, OF BRIDGEPORT, CONNECTICUT, ASSIGNOR TO THE SMITH & EGGE MFG. CO., OF BRIDGEPORT, CONNECTICUT, A CORPORATION OF CONNECTICUT.

LOCK CLAMP FOR CORDS.

Application filed August 5, 1927. Serial No. 210,827.

This invention relates to cord clamps but more particularly has reference to metal clamps such as are commonly employed for fastening the cord of sacks that are used in the postal service. Heretofore clamps of this description have been in service, but they could readily be loosened so that the contents of the sacks could be easily gotten at by unauthorized persons, and therefore devices of this nature are now so constructed that they can be locked in clamped condition, so as to necessitate the use of a proper key in order to release the cord and open the sack.

The object of the present invention is to provide a cord clamp which can be locked in the manner above referred to, and furthermore to so construct the clamp that it will be very durable and simple, while the ends of the cord of a mail sack can be threaded through the clamp with the greatest facility.

It is a still further object to provide a clamp that can be efficiently used whether a lock is or is not employed, since many business concerns and railroads use cord clamps for sacks merely as a convenient manner of closing the sacks for short transports, and consider the lock as unnecessary.

In order that a clear understanding may be had of the invention attention is called to the following detail description which is to be read in connection with the accompanying drawing in which

Figure 1 is a side elevation of the cord clamp with the parts in position for the insertion of the cord ends, the side of the housing for the clamping member being broken away.

Figure 2 is a plan view of the clamp as it is shown at Figure 1.

Figure 3 is a section at the line 3—3 of Figure 2.

Figure 4 is an end view of such construction.

Figure 5 is a side elevation, partly broken, showing the position of parts when the cord is partially clamped.

Figure 6 is a side elevation showing the position of parts when the cord is fully clamped and a padlock applied to lock the parts in clamped condition.

Figure 7 is a section at the line 7—7 of Figure 6.

Figure 8 is a detail plan view showing the clamping member and the operating lever in detached condition, and

Figure 9 is a similar view showing the clamping member and operating lever connected as in the completed article.

Similar numerals of reference denote like parts in the several figures of the drawing.

1 is any suitable base the outer face of which is shaped and formed so as to provide the usual way 2 for labels or address tags. At the inner end of the base and secured thereto is a housing 3 and at the other end of the base is the usual guide 4 for the ends of the cord, and secured to the base midway of the guide and housing is a flat upright staple 5.

6 is the clamping member whose rear extremity is pivoted within the housing near its rear upper portion thereof as shown at 7, 75 and 8 is the operating lever having an elongated slot 9 which, when the lever is depressed, embraces the staple 5, and for this reason this lever will be hereinafter termed a "hasp lever".

The hasp lever 8 is pivoted to the outer end of the clamping member 6, and any form of pivotal connection may be employed, although in this instance it is preferable, for sake of simplicity and cheapness, 85 to cut out the inner end of the hasp lever as shown at 10, thereby forming a bar 11, and the outer end of the clamping member is inserted through this cut out 10 and curled around the bar 11 so as to form the 90 pivotal connection.

The outer vertical walls of the housing 3 at the lower end are cut away so as to form shoulders 12, while the inner end of the hasp lever has projections 13 at each side thereof.

In applying the clamp the two ends of the cord from the sack are passed side by side through the passage-way denoted by the numeral 14 and between the clamping member 6 and base 1, and these cords pass on opposite sides of the staple 5 out through the guide 4.

The clamp is then pushed upward as far as it will go against the closed mouth of the sack, and the hasp lever 8 lowered and

depressed, and on the initial depression of this lever the projections 13 will be forced upward against the shoulders 12, thereby forcing the clamping member 6 against the 5 cords, and as the lever is depressed to its limit the clamping pressure against the cord will be increased, and when the hasp lever is completely depressed a shackle of an ordinary padlock 15 can be locked through 10 the staple 5, and thus secure the clamping member in its effective condition.

In order to greatly enhance the bite of the clamping member against the cord the bottom of the base may be provided with 15 spaced raised portions 16, and the clamping member itself may be formed with similar portions 17, and although these portions are very serviceable, nevertheless it is not necessary to provide but one of such portions near the outer end of the clamping member, and the invention is therefore not to be limited to the provision of raised or 20 depending clamping portions or to similar constructions such as serrations.

25 A denotes the cord to be clamped.

From an inspection of Figures 1 and 3 of the drawings it will be noted that the insertion of the ends of the cord through a clamp can be brought about with the greatest facility, and that when the hasp lever is depressed to its limit, as shown at Figure 6, it is not at all necessary to employ a lock, since the parts will remain in their clamped condition unless they are deliberately loosened, and, as before stated, because locks are required in some instances, this invention has been especially contrived with the end in view to provide for such lock.

40 While the shoulders 12 are formed on the housing 3, they may be formed on any special projections from the base but as the

housing is itself a projection from the base it is not deemed necessary to show any special projection.

45

I claim:—

1. A cord clamp comprising a base, a housing secured to the inner end of said base, the latter affording a passage-way for the cord, a clamping member whose rear end 50 is pivoted to the side walls of said housing immediately above said way, and a lever whose inner end is pivotally connected to the outer end of said member and engages a stationary part when the free end of the 55 lever is depressed whereby said member will be forced downwardly against the cord.

2. A cord clamp comprising a base, a housing secured thereto, a clamping member pivoted at its rear end to the side walls 60 of the housing, shoulders at the lower front portions of said walls, a lever having pivotal connection with the front end of said member and adapted when depressed to engage said shoulders, and a cord passage-way 65 beneath said member and lever, whereby, when said lever is depressed it will engage said shoulders and force said member downwardly against a cord inserted in said passage-way.

3. A construction as in claim 1, in which the inner end of the clamping member is pivoted near the upper portions of the side walls to allow free passage of the cord beneath said member.

70 4. A construction as in claim 1, in which an upright staple is secured to the base, while the lever has therein an elongated slot which embraces said staple when the lever is depressed, whereby said lever may be 75 locked.

In testimony whereof I affix my signature hereto.

ALFRED H. SORELL.
